(57) **CLAIM**

The ornamental design for a mold for confectionery, as shown and described.

DESCRIPTION

FIG. 1 is a first perspective view of a mold for confectionery showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is a sectional view thereof, taken along line 9-9 in FIG. 3.

The broken lines shown in the FIGS. 2 and 8 depict portions of the mold for confectionery that form no part of the claim. The broken lines shown in FIG. 3 indicate the cross-section of FIG. 9.
